CLAIM

The ornamental design for a cremation display, as shown and described.

DESCRIPTION

FIG. 1 is a front elevational view of a cremation display showing my new design;

FIG. 2 is a side elevational view of the cremation display with the opposite side being a mirror image of the same;

FIG. 3 is a back view of the cremation display;

FIG. 4 is a top plan view of the cremation display; and,

FIG. 5 is a bottom plan view of the cremation display. The broken line showing of the urns, casket, pictures, flowers, plant, and shelf in FIGS. 1, 2, 4, and 5 is for illustrative purposes only and forms no part of the claimed design.
